Primary Examiner — George D Kirschbaum*Assistant Examiner* — Amy Wierenga(74) *Attorney, Agent, or Firm* — Kilpatrick Townsend & Stockton, LLP(57) **CLAIM**

The ornamental design for a pipe cuff, as shown and described.

DESCRIPTION

FIG. 1 is a side view of a pipe cuff, with all sides being identical.

FIG. 2 is an end view of the pipe cuff of FIG. 1; and, FIG. 3 is perspective side view of the pipe cuff of FIG. 1, shown attached to another pipe cuff section.

The broken lines shown in the drawing depict environmental subject matter only and form no part of the claim.
